DESIGN FOR AN OIL BAR

Erling G. Fossum and Francis Lawrence Ayres,
Chicago, Ill., assignors to Stewart-Warner Corporation, Chicago, Ill., a corporation of Virginia

Application March 8, 1946, Serial No. 127,223

Term of patent 14 years

(Cl. D52—2)

To all whom it may concern:

Be it known that we, Erling G. Fossum and Francis Lawrence Ayres, citizens of the United States, residing at Chicago, in the county of Cook and State of Illinois, have invented a new, original, and ornamental Design for an Oil Bar, of which the following is a specification, reference being had to the accompanying drawing, forming part thereof.

The figure is a perspective view of an oil bar, showing our new design.

The back and right side of the bar are similar in appearance to the left side.

We claim:

The ornamental design for an oil bar, substantially as shown and described.

ERLING G. FOSSUM.

FRANCIS LAWRENCE AYRES.
